UNITED STATES PATENT OFFICE

108,420

DESIGN FOR A DISPLAY CASE FOR WATCHES

Abraham S. Braude, Chicago, Ill.

Application December 6, 1937, Serial No. 73,385

Term of patent 3½ years

To all whom it may concern:

Be it known that I, Abraham S. Braude, a citizen of the United States of America, residing at Chicago, in the county of Cook and State of Illinois, have invented a new, original, and ornamental Design for Display Cases for Watches, of which the following is a specification; reference being had to the accompanying drawing, forming a part thereof.

Fig. 1 is a perspective view of a display case for watches showing my design in closed position.

Fig. 2 is a view similar to Fig. 1, with the case in open position.

Fig. 3 is an end view.

I claim:

The ornamental design for a display case for watches, as shown. ABRAHAM S. BRAUDE.
